RELAY SWITCH

Edward M. Ashworth, Frank F. Ambuhl, and Henry W. Smith, Toronto, Ontario, Canada, assignors to Toronto Electric Commissioners, Toronto, Ontario, Canada

Application January 12, 1933, Serial No. 651,346

1 Claim. (Cl. 200—87)

The principal objects of this invention are to devise a very simple and positive form of relay, particularly applicable for a control system, which will automatically assume a neutral position when the circuits controlling its operation are open.

A further and important feature is to provide a relay which will be reliable in its operation and which will directly control the switching 10 elements in electric circuits eliminating the necessity for the use of auxiliary relays.

The principal feature of the invention consists in the novel arrangement of balancing tension springs connected with the armature of an electro-magnetic oscillating relay to hold it in a neutral position with the switch element mounted thereon clear of the circuit contacts controlled thereby, said armature being operable to swing in either direction from the neutral position 20 to move the switch element to engage the contacts to close either of the controlled circuits.

In the accompanying drawing Figure 1 is a front elevation of the relay, parts thereof being broken away.

25 Figure 2 is a side elevational view.

In the construction herein shown, a laminated core 1 is formed with a pair of parallel uprights 2 and 3 and a central upright member 4 spaced centrally therebetween, the central 30 member being shorter than the others and having an arc-shaped end surface. This core is mounted upon a plurality of studs 5 which are rigid with the mounting plate 6.

Electro-magnetic coils 7 and 8 are wound upon 35 the members 2 and 3 respectively and these are connected in a suitably controlled circuit to direct a current through either one or the other as may be desired.

A pair of parallelly arranged bars 9 are secured to and extend between the upper ends 40 of the side cores 2 and 3 and a spindle 10 is horizontally journaled in said bars centrally of the length thereof.

An oscillating armature 11 is rigidly mounted 45 upon the spindle 10 having the ends of the horizontal portion thereof extending into close proximity to the arc-shaped surfaces of the magnet cores 2 and 3, and a central downwardly depending leg 12 of said armature extends into 50 close relationship to the arc-shaped end surface of the centre core member 4.

A pair of brackets 13 which are formed rigid 55 with the mounting plate 6 extend past the ends of the laminated core and support a horizontal plate 14. A pair of blocks 15 and 16 of insulat-

ing material are mounted on the plate 14 equidistant from the centre thereof and on each of said blocks are mounted a pair of spring contacts 17 and 18 which are connected with suitable leads 19 to binding screws 20 on the mounting plate.

5 A bar 21 is rigidly mounted on the end of the spindle 10 projecting over the plate 14 and coiled tension springs 22 and 23 are secured to the ends thereof and extending downwardly are 10 connected to the plate 14 by the adjustable rods 24 and 25 respectively.

A tongue 26 extends downwardly from the centre of the bar 21 and has mounted on the end thereof a transverse bar 27 to which are 15 secured the insulated contact plates 28 and 29 which upon the swinging of the bar 21 engage and close the contacts 17 or 18.

It will be understood that when a current is directed through the coil 7 a magnetic flux is established through the core 2, armature 11 and centre core 4 which will swing the armature on its pivot against the tension of the spring 23 thereby swinging the contact plate 29 into engagement with the flexible contacts 18, and 25 thereby closing an electric circuit which may be for operating a circuit breaker or other device.

When a current is directed through the coil 8 a similar magnetic flux is established through the core 3, armature 11 and centre core 4 which 30 has the effect of swinging the armature against the tension of the spring 22 and closing the circuit connected with the contacts 17.

The entire structure is enclosed by a cover 35 31 which is clamped against the plate 6 by nuts threaded on studs 32 extending from the brackets 13. The cover is preferably provided with a small opening 33 in its front side giving access to the switch contacts and is closed by 40 a door 34.

The switch circuit will be retained closed so long as the current through the controlling magnet coil is sustained, but immediately upon the opening of the magnet coil circuits, the spring 45 22 or 23 whichever is in tension will swing the armature back to a neutral position where it is held by the balancing springs 22 and 23 out of contact with the contacts 17 and 18.

A device such as described is extremely simple in operation; is very rugged in structure and will remain in operation without attention for an indefinite period of time, functioning positively upon the closing of an electric circuit through either one of its magnetic coils.

What we claim as our invention is:—
A relay switch comprising in combination a
magnet core having a central pole member and
spaced pole members, magnet windings on said
5 spaced pole members, said central and spaced
pole members having their ends disposed in a
path substantially concentric of a common cen-
tre, an armature mounted to oscillate on said
common centre and having triple pole ends
10 swinging into close non-contacting relation to
said pole ends, switch means selectively operated
by said armature and acting to limit the swing.

ing movement thereof in either direction, and means for urging said armature to a neutral position, said central pole member serving in a co-operative capacity to each of said spaced pole members on the respective energizing thereof to form a direct path for the magnetic flux through the adjacent one of the triple armature poles whereby a strong operating influence is imparted to the armature with the minimum current flow.
